CAN FORMING MACHINE

Mark E. Moore, Maywood, Ill.

Application October 6, 1936, Serial No. 104,301

12 Claims.

(Cl. 113—46)

The invention relates generally to the art of can making and has for an object to provide a new and improved apparatus for forming seamless cans.

5 In its more detailed nature the invention resides in the provision of a novel can forming apparatus in which the can shaping channel or die opening is formed by a plurality of rollers rotatable in unison in planes intersecting the axis of said opening, and in which a plurality of blank holding and pre-shaping rings successively press a blank against the rollers, after which a plunger forces the partially shaped blanks through the rollers while they are being rotated whereby to subject the blank to a combination drawing and rolling engagement ultimately forming said blank into a seamless can including an integral bottom.

With the above and other objects in view that will hereinafter appear, the invention further resides in the novel construction and arrangement of parts particularly pointed out in the following detailed description and the appended claims, and illustrated in the accompanying drawings.

In the drawings:

25 Figure 1 is a front elevation and part section illustrating a can forming machine embodying my invention,

Figure 2 is a vertical cross section of the machine shown in Figure 1,

30 Figure 3 is a detail plan view of one of the forming rollers,

Figure 4 is a side elevation of one of the roller mounting and spacing segments,

35 Figure 5 is a plan view of the segment shown in Figure 4,

Figure 6 is a side elevation of my improved form of can body,

Figure 7 is a vertical cross section of the can body,

40 Figure 8 is a horizontal section taken on the line 8—8 on Figure 2,

Figure 9 is a horizontal section taken on the line 9—9 on Figure 2,

45 Figure 10 is a diagrammatic sectional view of the can forming parts of the machine with the can forming rings and plunger elevated and a can blank supported on the forming rollers,

Figure 11 is a view similar to Figure 10 with the plunger and ring equipment lowered into the position in which the outermost ring section grips the blank upon the rollers,

50 Figure 12 is a view similar to Figure 11 showing the plunger and ring equipment lowered to the point where the intermediate ring exercises its pre-shaping function,

Figure 13 is a view similar to Figure 12 with the plunger ring equipment lowered to the point at which the innermost ring section exercises its pre-shaping function, and

5 Figure 14 is a view similar to Figure 13 illustrating the plunger as lowered to its maximum position and the shell elevated to its maximum position, the rollers having been rotated by said shell for cooperating with the descending plunger in the final forming operation.

10 In the drawings in which like numerals of reference indicate like parts in all of the figures, 5 designates the base portion of the machine, 6 the bed, 7 the superstructure side standards which are joined by a cross web 8, and 9 a pair of parallel spaced cheek plates suitably supported upon the frame superstructure. It is to be understood that any suitable form of press frame structure may be employed to support the novel mechanism embodied in my improved machine.

15 The frame standards 7 provide suitable bearings for the power shaft 10 on which is carried an inner pair of crank discs 11 including the crank portion 12. The discs 11 are provided in their outer faces with suitable cam grooves 13. The shaft 10 also carries an outer pair of cam discs 14 having suitable cam grooves 15 in their inner faces and a driven sprocket 16 which may be disposed inside or outside the frame. The shaft is also extended as at 17 for connection with any 20 suitable power applying means (not shown).

25 The bed 6 is recessed as at 18 to receive a mounting ring 19 which embraces a plurality of spaced bearing segments 20, see Figures 4, 5 and 8. Each of the segments is provided at its companion segment opposing surfaces with individual hub recesses 21. The segments also each include a ring seat 22 for fitting the mounting ring 19, a draw ring seat 23, and a rack clearance cut-out portion 24. The segment seats 23 cooperate when 30 assembled to form a mounting for the draw ring 25, as shown in Figures 1 and 2 of the drawings.

35 The forming rollers 26 each include bearing trunnions 27 receivable in the segment recesses 21 and which are surrounded by ball bearings 28 packed in heavy grease when the rollers and segments are assembled, as shown in Figure 8. The rollers are provided with concave can forming peripheral portions 30 collectively forming a circular shaping channel or die opening, and it will be observed that the individual planes of rotation of the rollers all intersect the axis of this opening. Each roller also includes a gear sector 31 which extends from the one side face of the roller through approximately one-third of the 40

periphery thereof. The pitch line of each sector preferably coincides with the diameter of the forming surface of the particular roller so that the shell and roller movement will conform properly with the movement of the plunger.

5 A roller actuating shell or ring 32 surrounds the roller assembly and is provided with a plurality of racks 33, one thereof being positioned to mesh with each of the roller gear sectors as 10 shown in Figures 2 and 8. The shell is carried by a pair of arms 34 guided in grooves 35 formed in the outer faces of the cheek plates 9 and equipped at their upper ends with rollers 36 operable in the grooves 15 of the cam discs 14.

15 The inner faces of the cheek plates 9 are grooved as at 37 to slidably receive the cross head 38 which is connected by a pitman 39 with the disc crank 12 and which carries the forming plunger 40. The plunger 40 is suitably shaped at its lower end as at 41 to suitably shape the bottom end of the can, and is provided with an air duct 42 to break the vacuum which would otherwise be created by removal of a formed can from the plunger, thus facilitating delivery of the formed 25 can.

Surrounding the plunger 40 and movable at times therewith is a ring head 43 including an inner ring blank forming portion 44 and a head flange 45. An intermediate blank forming ring 30 46 and an outer blank holding ring 47 are yieldably suspended from the head flange 45 on mounting pins 48, coil springs 49 being interposed between said rings and flange for normally holding the rings in the position illustrated in Figure 35 10 of the drawings.

35 The holding and pre-shaping ring assemblies 43, 46, 47 are supported on rods 50 which pass upwardly through accommodating openings in the cross rod 38 and connect with the slide head 40 51 which is guided in the inner grooves 39 formed in the cheek plates 9. Rollers 52 project inwardly from the slide head and operate in the grooves 13 formed in the cam and crank plates 11.

45 A can bottom forming plunger 53 is provided and has its upper end 54 shaped to cooperate with the plunger end 41 in shaping the bottom of the can. The plunger 53 is suitably guided as at 55 and is equipped with a roller 56 engaged by a cam 57 for lifting and lowering the plunger 50 in timed relation to the main forming plunger 40. The cam 57 is mounted upon a shaft 58 having rotative bearing in the base frame and which includes the driven sprocket 59 to which 55 rotation is imparted through the transmission chain 60 from the driver sprocket 16.

The operation of my improved machine and the steps of my improved method are diagrammatically illustrated in Figures 10 through 14. 60 In the first step in the method and the operation of the machine a blank B is positioned upon the rollers 26 as shown in Figure 10. The shaft 10 is continuously rotated but the discs 11 and 14 are provided with a dwell portion so that the 65 parts have a period of rest in the position shown in this figure. The first movement is a collective movement downwardly of the plunger 40 and the collection of rings 44, 46, and 47, and Figure 11 illustrates the first contact, it being that of the 70 outermost ring 47 with the roller supported blank, serving to hold the blank against the rollers.

Upon continued movement downwardly of the plunger and ring equipments the outermost ring 75 47 will remain in the holding position above de-

scribed and the plunger 40 and rings 44 and 46 will move to the position shown in Figure 12 in which the intermediate ring 46 exercises its function of pre-shaping the can blank against the supporting surfaces of the rollers.

5 Upon continued movement downwardly of the plunger 40 and the remaining ring portion 43, the latter will assume the position illustrated in Figure 13 and will exert its pre-shaping pressure against the can blank and the supporting rollers.

By the successive contacts of the pre-shaping rings above described the blank is pre-shaped into a substantially frusto-coniform shape by pressures exerted at circular areas successively inwardly of the clamped periphery. In this 15 manner the pre-shaping of the blank is formed without excessive center strain or metal distortion and this manner of shaping contributes much toward the formation of a one-piece, seamless can, the integral bottom of which is not subjected to weakening strains and metal distortion.

20 At this time the dwell in the cam grooves 15 is about exhausted and these grooves are to become effective to lift the shell 32 as shown in Figures 25 1 and 2. At the same time the dwell in the disc grooves 13 becomes effective and the holding and pre-shaping ring assembly has terminated its downward movement. The main plunger 40, however, continues its descent in engagement 30 with the can blank. Thus the plunger will continue its downward movement while the shell 32 is being raised to impart rotation to the forming rollers 26. Thus the can body is formed by a composite drawing and rolling contact. The surface speed of the rollers being substantially that of the opposed surfaces of the plunger 40, the metal of the can blank will not be subjected to any sliding contact and because of the fact that the said walls of the blank are tightly gripped 40 between the rollers and the opposed plunger surfaces the blank will not be subjected to any strain and distortion across the integral bottom forming wall.

45 The ultimate position of the parts upon completion of the actual can shaping is shown in Figure 14. The can, as formed, is forced through the draw ring 25 but it is to be understood that this ring is not necessary and may be dispensed with if desired.

50 As the plunger 40 reaches the lower limit of its stroke it is opposed by the bottom forming plunger 53 and after the shaping parts return to their normal position, as shown in Figure 10, the bottom forming plunger 53 is returned to its lowered position and the formed can is discharged into the receiving chute 61, as shown in Figure 2.

55 In Figures 6 and 7 I have illustrated my improved can which includes the side walls 62 and the integral bottom 63 shaped by the opposed 60 plungers 41 and 54 in any suitable manner as illustrated at 64.

65 If desired, the portion of each roller which does not actually contact with and form the can blank may be made flat or cylindrical as at 65 (see Figure 3) and presented for rolling contact with bearing rails 66 mounted in the shell 32 as shown in Figure 8. Thus each roller will roll between the plunger carried blank and the shell in the manner in which one rolls a pencil between the 70 palms of oppositely moving hands, thus relieving the bearings of strains.

70 My improved machine may also be employed in the formation of tubes such as are mounted upon the cylinders used in rotogravure work, or tubes 75

used for various other purposes. All that is necessary to form such tubes is to shape the blanks as hereinbefore described and then remove the bottoms from the units formed as shown in Figures 6 and 7 thus transforming them into tubes.

It is of course to be understood that the details of structure and arrangement of parts may be variously changed and modified without departing from the spirit and scope of my invention. If desired a square or oblong plunger and die rollers of complementary shape can be employed so that cans other than the more common cylindrical type can be formed.

I claim:

15. 1. In can forming apparatus, a generally toroidal blank support formed of a plurality of rollers arranged so that their peripheries define a central opening of the size of a can-to-be-formed, means movable toward and from said support and operative in successive stages for pre-shaping said blank in generally frusto-coniform shape and for thereafter forcing said pre-shaped blank through said opening to complete the can formation, and means for rotating the rollers during the forcing of the preshaped blank therethrough.

20. 2. In can forming apparatus, a generally toroidal blank support formed of a plurality of rollers arranged so that their peripheries define a central opening of the size of a can-to-be-formed, means movable toward and from said support and operative in successive stages for pre-shaping said blank in generally frusto-coniform shape and for thereafter forcing said pre-shaped blank through said opening to complete the can formation, said means including concentric rings engageable with the blank successively and a central plunger for forcing the pre-shaped blank through said opening to complete the can formation, and means for rotating the rollers during the forcing of the pre-shaped blank therethrough.

25. 3. In can forming apparatus, a generally toroidal blank support defining a central opening of the size of a can-to-be-formed, and means movable toward and from said support and operative in successive stages for pre-shaping said blank in generally frusto-coniform shape and for thereafter forcing said pre-shaped blank through said opening to complete the can formation, said means including an inner ring having a flange, an intermediate ring, and an outer ring engageable with the blank successively inwardly beginning with said outer ring, means supporting said intermediate and outer rings on said flange for yieldable engagement with a blank on said toroidal support, and a central plunger movable with the rings during pre-shaping of the blank and thereafter movable through said rings for forcing the pre-shaped blank through said opening to complete the can formation.

30. 4. In can forming apparatus, a blank supporting means of generally toroidal shape defining a central opening of the size of a can-to-be-formed and comprising a multiplicity of rollers having concaved peripheries collectively defining the opening and positioned with their planes of rotation intersecting the axis of said opening, means for forcing a blank onto said rollers and through said opening, and means for holding the rollers stationary during the forcing of the blank thereonto and for positively rotating the rollers during the forcing of the blank therethrough.

35. 5. In can forming apparatus, a blank supporting means of generally toroidal shape defining a central opening of the size of a can-to-be-formed and comprising a multiplicity of rollers having

concaved peripheries collectively defining the opening and positioned with their planes of rotation intersecting the axis of said opening, means for forcing a blank onto said rollers and through said opening including a plurality of rings successively engageable to press a blank into conformity with the engaged contour of said rollers and a central plunger movable with and through said rings for forcing the blank through said opening to complete the can formation, and means for holding the rollers stationary during the forcing of the blank thereonto and for positively rotating the rollers during the forcing of the blank therethrough.

40. 6. In can forming apparatus, a blank supporting means of generally toroidal shape defining a central opening of the size of a can-to-be-formed and comprising a multiplicity of rollers having concaved peripheries collectively defining the opening and positioned with their planes of rotation intersecting the axis of said opening, and means for imparting rotation to said rollers, said last named means comprising a longitudinally movable shell surrounding said rollers, racks carried by said shell and gear sectors carried one on each roller and meshing with said racks.

45. 7. In can forming apparatus, a multiplicity of rollers having concaved peripheries collectively defining a forming opening and positioned with their planes of rotation intersecting the axis of said opening, means for forcing a blank onto said rollers and through said opening including a plurality of rings successively engageable to press a blank into conformity with the engaged contour of said rollers and a central plunger, and means for moving the rings and plunger together to pre-shape the blank and to thereafter move the plunger alone and impart rotation to said rollers to complete the shaping of the can between said plunger and rollers.

50. 8. In can forming apparatus, a multiplicity of rollers having concaved peripheries collectively defining a forming opening and positioned with their planes of rotation intersecting the axis of said opening, means for forcing a blank onto said rollers and through said opening including a plurality of rings successively engageable to press a blank into conformity with the engaged contour of said rollers and a central plunger, and means for moving the rings and plunger together to pre-shape the blank and to thereafter move the plunger alone and impart rotation to said rollers to complete the shaping of the can between said plunger and rollers, said last named means including a longitudinally movable shell surrounding said rollers, racks carried by said rollers, and gear sectors carried one on each roller and meshing with said racks.

55. 9. In can forming apparatus, a generally toroidal blank support formed of a plurality of rollers arranged so that their peripheries define a central opening of the size of a can-to-be-formed, means movable toward and from said support and operative in successive stages for pre-shaping said blank in generally frusto-coniform shape and for thereafter forcing said pre-shaped blank through said opening to complete the can formation, means for rotating the rollers during the forcing of the preshaped blank therethrough, and a bottom plunger movable in opposition to said forcing means for shaping the bottom of the formed can.

60. 10. In can forming apparatus, a blank supporting means of generally toroidal shape defining a central opening of the size of a can-to-be-formed

and comprising a multiplicity of rollers having concaved peripheries collectively defining the opening and positioned with their planes of rotation intersecting the axis of said opening, and means for imparting rotation to said rollers comprising a longitudinally movable shell surrounding said rollers, racks carried by said shell, and gear sectors carried one on each roller and meshing with said racks, the pitch line of each sector substantially coinciding with the diameter of the peripheral forming portion of the roller by which it is carried.

11. In can forming apparatus, a blank supporting means of generally toroidal shape defining a central opening of the size of a can-to-be-formed 15 and comprising a multiplicity of rollers having concaved peripheries collectively defining the opening and positioned with their planes of rota-

tion intersecting the axis of said opening; means for imparting rotation to said rollers comprising a longitudinal shell surrounding said rollers, racks carried by said shell, and gear sectors carried one on each roller and meshing with said racks, and longitudinally disposed tracks carried by the shell and presented for rolling contact by said rollers.

12. In can forming apparatus, a blank supporting means composed of a plurality of rollers disposed to collectively define a die opening, a 10 plunger movable axially in a direction at right angles to the axes of the rollers for forcing a blank through said opening, and means for positively rotating the rollers at the same surface speed as the plunger during the forcing of the 15 blank therethrough.

MARK E. MOORE.
